UNITED STATES PATENT OFFICE.

MICHAEL J. GASPER, OF HAZLETON, PENNSYLVANIA.

1,192,296.

COAL-JIG.

Specification of Letters Patent. Patented July 25, 1916.

Application filed March 25, 1916. Serial No. 86,635.

To all whom it may concern:

Be it known that I, MICHAEL J. GASPER, a citizen of the United States, residing at Hazleton, in the county of Luzerne and State 5 of Pennsylvania, have invented new and useful Improvements in Coal-Jigs, of which the following is a specification.

This invention relates to that class of devices which are generally known as coal jigs 10 or jiggers and in which separation of the relatively light coal from the relatively heavy refuse, such as rock and slate, is effected by the action of water which is caused to pulsate through an inclined screen over 15 which the mixture of coal and refuse as it comes from the mine is guided.

The invention has for its object to produce a device of simple and improved construction having a gate, known as the "slate 20 gate" through which the heavy refuse is discharged, and means for automatically actuating said gate when a sufficient quantity of refuse material is accumulated.

A further object of the invention is to 25 simplify and improve the general construction and arrangement of the parts constituting the improved device.

With these and other ends in view which 30 will readily appear as the nature of the invention is better understood, the same consists in the improved construction and novel arrangement and combination of parts which will be hereinafter fully described and particularly pointed out in the claims.

In the accompanying drawings has been 35 illustrated a simple and preferred form of the invention, it being, however, understood that no limitation is necessarily made to the precise structural details therein exhibited, but that changes, alterations and modifications within the scope of the claims may be 40 resorted to when desired.

In the drawings.—Figure 1 is a side elevation of a coal jigger constructed in accordance with the invention, parts having been broken away. Fig. 2 is a top plan view with parts broken away. Fig. 3 is a front elevation with parts broken away. Fig. 4 is a detail view, partly in section and partly 45 in elevation, showing the manner of supporting the rock shaft carrying the gate actuating arms and the counterweight arms. Fig. 5 is a detail view, partly in section and partly in elevation, showing a portion of the

plunger stem and the means on said stem 55 for engaging the arm of the rock shaft.

Corresponding parts in the several figures are denoted by like characters of reference.

The tank 15 supports the inclined grate or screen 16 through which water is caused to 60 pulsate by well known means, not shown. At the discharge end of the tank is the wall member 17 at the lower end of which the slate gate 18 is supported by a hinge 19, permitting said gate to swing outwardly 65 from the tank. The coal receiving chute 20 is connected with the upper edge of the wall member 17 where the coal overflows; the slate chute 21 is supported to receive the refuse coming over the grate or screen 16 70 when the gate 18 is open.

The upper portion of the tank is provided with bearings or brackets 22 through which are threaded screws 23 that serve to support the rock shaft 24, said rock shaft and 75 screws having interengaging conical points 25 and sockets 26 that will permit said rock shaft to operate freely, wear on the bearings being compensated for by proper adjustment of the said screws 23. The rock shaft 80 24 has radial arms 27 that are connected by link bars 28 with the gate 18. The rock shaft 84 is also provided with arms 29 carrying counterweights 30 that tend to maintain the gate 18 in a closed position. The weights 85 30 are adjustably mounted on the arms 29 by set screws 31.

A cross bar 32 extending across the top of the tank supports a downwardly extending cylinder 33 which is made of screen material, such as woven wire, perforated sheet metal or the like, said screen cylinder serving as a guide for a vertically movable plunger 34 which is likewise made of screen material and of cylindrical shape. The cylindrical guide member 33 is cut away at its lower portion to produce a curved or inclined recess 35 facing the wall member 17 of the tank. The cut-away portion or recess 35 will facilitate the escape of slate, rock 100 and other obstructions when the slate gate is thrown open and will prevent such material from becoming entangled with the cylindrical guide member.

The plunger 34 has an upwardly extending rod or stem 36 which is guided through a tube 37 mounted and supported on the cross bar 32, and said stem carries a collar

38 that may be secured in position at various adjustments by a set screw 39, said collar serving by contact with the upper end of the guide tube 37 to limit the downward movement of the plunger. The set screw 39, in addition to securing the collar 38, is utilized as an engaging member to engage beneath an arm 40 extending radially from the rock shaft 24, said rock shaft being thus rocked against the tension exerted by the 10 counterweights 30 when the plunger 34 and the stem 36 move in an upward direction.

In the operation of this device the coal and refuse coming from the mine is guided 15 over the inclined screen 16 in the direction of the slate gate 18. By pulsation of water through the screen the coal being relatively light is carried upward and is permitted to escape over the top edge of the 20 wall member 17, being received in the chute 20. When a predetermined quantity of refuse, such as slate and rocks, has accumulated in the lower portion of the tank adjacent to the slate gate, pressure will be exerted upwardly against the plunger 34, 25 causing the latter to rise and to actuate the rock shaft whereby the slate gate is thrown open, permitting the accumulated slate and rock to pass into the chute 21. As soon as 30 the pressure against the slate gate is relieved, the latter will be restored to its closed position by the action of the counterweights 30, the plunger 34 settling to its initial position in the lower end of the cylindrical screen 33 which constitutes a guide 35 for the plunger. The guide cylinder 33, as well as the plunger 34, being made of screen material, neither one nor the other of said members will obstruct the pulsation of the water, and the operation of the device is, 40 therefore, facilitated and improved.

Having thus described the invention, what is claimed as new, is:—

1. In a device of the class described, a jig 45 tank having an inclined screen bottom and a slate gate hingedly supported above the low end of said screen bottom with its free edge adjacent thereto, means including a rock shaft having radial arms, and connecting links or bars for controlling the movement of the gate, and means including a vertically movable floating plunger for actuating the rock shaft, said plunger having a predetermined limited movement independently of its connection with the rock shaft.

2. In a device of the class described, a jig 50 tank having an inclined screen bottom and a slate gate hingedly supported above the low end of said screen bottom with its free edge adjacent thereto, means including a rock shaft having radial arms, and connecting links or bars for controlling the movement of the gate, and means including a vertically movable floating plunger for actuating the rock shaft, said plunger having a pre-

determined limited movement independently of its connection with the rock shaft, said rock shaft having radially extending weight carrying arms to balance the weight of the slate gate.

3. In a device of the class described, a jig 70 tank having a slate gate, actuating means for said gate including a rock shaft and suitable connections, adjustable counterweights connected with the rock shaft to maintain the slate gate normally in closed position, and gate actuating means including an arm extending from the rock shaft, a plunger guided for vertical movement in the tank and having an upwardly extending stem, and engaging means on said stem for the radial arm of the rock shaft, and a guide for said plunger having its lower end reduced to form an inclined recess.

4. In a device of the class described, a jig 85 tank having a front wall over which coal may flow, and a slate gate hinged at the lower edge of said wall, operating means for closing the gate including a rock shaft, connections between said shaft and the gate, and counterweight carrying arms extending from the rock shaft, and operating means for opening the gate including a vertically movable plunger, an arm extending from the rock shaft, a plunger stem, and arm engaging means adjustably mounted on said stem whereby the plunger and the plunger stem may have a predetermined limited movement with respect to the arm extending from the rock shaft.

5. In a device of the class described, a jig 90 tank having a front wall over which coal may flow, and a slate gate hinged at the lower edge of said wall, operating means for closing the gate including a rock shaft, connections between said shaft and the gate, and counterweight carrying arms extending from the rock shaft, and operating means for opening the gate including a vertically 95 movable plunger, an arm extending from the rock shaft, a plunger stem, and arm engaging means on said stem, and a cylindrical guide for said plunger, said guide being provided at its lower end with a reduced portion forming a recess facing the wall with which the slate gate is connected.

6. In a device of the class described, a jig 100 tank having a front wall over which coal may flow, and a slate gate hinged at the 105 lower edge of said wall, operating means for closing the gate including a rock shaft, connections between said shaft and the gate, and counterweight carrying arms extending from the rock shaft, and operating means for opening the gate including a vertically 110 movable plunger, an arm extending from the rock shaft, a plunger stem, and arm engaging means on said stem; and guide means 115 for the plunger consisting of a screen cylinder.

der supported within the tank and having a reduced lower portion forming a recess facing the slate gate.

7. In a device of the class described, a jig tank having a slate gate, actuating means for said gate including a rock shaft and suitable connections, adjustable counter-weights connected with the rock shaft to maintain the slate gate normally in closed position, and gate actuating means including an arm extending from the rock shaft, a plunger of screen material guided for vertical movement in the tank and having an upwardly extending stem, and engaging means on said stem for the radial arm of the rock shaft.

8. In a device of the class described, a jig tank having a slate gate, actuating means for said gate including a rock shaft and suitable connections, adjustable counter-

weights connected with the rock shaft to maintain the slate gate normally in closed position, and gate actuating means including an arm extending from the rock shaft, a plunger of screen material guided for vertical movement in the tank and having an upwardly extending stem, and engaging means on said stem for the radial arm of the rock shaft; the guiding means for the plunger being composed of a cylindrical member of screen material having its lower end cut off obliquely to form a recess facing the slate gate.

In testimony whereof I affix my signature in presence of two witnesses.

MICHAEL J. GASPER.
